UNITED STATES PATENT OFFICE.

SAM HERSCHE, OF CLEVELAND, OHIO.

HUMIDIFIER.

Application filed January 23, 1925. Serial No. 4,334.

It is customary to provide in hot air furnaces air-humidifying means comprising a receptacle into which water may be introduced from the exterior of the furnace and from which this water may evaporate into the air current. As these receptacles are constructed at the present time, however, there is no way to close the opening through which the water evaporates into the air current and accordingly water being poured into the receptacle very often splashes over in appreciable quantity into the interior of the furnace where it produces obvious detrimental results. The principle object of my invention is to provide humidifying means of this type free from this objection. In the drawings accompanying this application and forming a part thereof I have shown, for purposes of illustration, three forms which my invention may assume. In these drawings:

Figure 1 is a fragmentary side elevation of a furnace embodying the first of these three illustrative forms.

Figure 2 is a fragmentary section on the line 2—2 of Figure 1.

Figure 3 is a fragmentary section on the line 3—3 of Figure 2.

Figures 4 and 5 are fragmentary sections similar to Figure 3 showing optional methods of supporting the cover on the receptacle,

Figure 6 is a view similar to Figure 1 showing the second of the three alternative forms,

Figure 7 is a section on the line 7—7 of Figure 6,

Figure 8 is a fragmentary horizontal section above the top of the receptacle showing the third of the three alternative forms with the cover in one position, while

Figure 9 is a view similar to Figure 8 showing the cover in alternative position.

The embodiment of my invention disclosed in Figures 1 through 3 comprises a receptacle 11 supported by the base plate 12 of the furnace 13 in position extending through and closing an aperture 14 in the furnace wall 15, and provided with an open top 16 divided by the furnace wall 15 into an outer opening 17 through which water may be inserted into the receptacle 11 and an inner opening 18 through which water may evaporate into the air current within the furnace wall 15. Mounted upon this receptacle 11, by means of trunnions 19 pivotally support-

ed in arcuate projections 20 on the side walls 21 of the receptacle 11, is a cover 22 comprising an outer portion 23 arranged to overlie and close the outer opening 17 and an inner portion 24 arranged to overlie and close the inner opening 18 but disposed at an angle to the outer portion 23 so that when the outer portion 23 is in position closing the outer opening 17 the inner portion 24 is raised from the inner opening 18 as shown in full lines in Figure 2 and when the inner portion 24 is in position closing the inner opening 18 the outer portion 23 is raised from the outer opening 17 as shown in dotted lines in Figure 2.

In Figures 4 and 5 I have shown optional forms of supporting the cover from the receptacle, the form in Figure 4 comprising trunnions 25 carried by the cover 26 and pivotally supported in arcuate projections 27 extending exteriorly of the side walls 28 of the receptacle 29, and the form in Figure 5 comprising trunnions 30 carried by the cover 31 and pivotally supported in recesses 32 formed directly on the side walls 33 of the receptacle 34.

In the embodiment of my invention shown in Figures 6 and 7 the receptacle 35 is again supported upon the base plate 12 of the furnace 13 and projecting through the opening 14 in the furnace side wall 15 with its open top 36 similarly divided into an outer opening 37 for the insertion of the water and an inner opening 38 for the evaporation of the water into the air current. In this form, however, a cover 39 is reciprocably mounted upon the receptacle 35 by means of lower guides 40 and upper guides 41 extending inwardly from the two end walls 42 of the receptacle 35 below and above the edges 43 of the cover 39, and this cover is reciprocable between an outer position closing the outer opening 37 as shown in full lines in Figure 7 and an inner position closing the inner opening 38 as shown in dotted lines in Figure 7. In this construction reciprocation of the cover 39 is facilitated by the upturned forward edge 44 and excess outward movement is deterred by the upturned inner cover edge 45.

It will be obvious, however, that I may omit the upper guides 41 and also that I may omit either or both of the upturned edges 44 and 45.

In the form of my invention disclosed in Figures 8 and 9 the receptacle 46 is sup-

ported and positioned in the same manner and provided with the open top 47 divided by the furnace wall 48 into the inner opening 49 and the outer opening 50. In this form, 5 however, the receptacle 46 is provided with an ear 51 arranged to pivotally support a horizontally swinging cover 52 comprising an outer part 53 arranged to overlie and close the outer opening 50 and an inner part 10 54 arranged to overlie and close the inner opening 49 but disposed in relation to the outer part 53 in such manner that when the outer part 53 is in the position shown in Figure 8 exposing the outer opening 50 the inner part 54 is in position closing the inner opening 49, and when the inner part 54 is in the position shown in Figure 9 exposing the inner opening 49 the outer part 53 is in position closing the outer opening 50.

20 It will be apparent that each of the three embodiments of my invention herein shown provides a closure for the inner receptacle opening and therefore provides means to prevent water splashing into the interior of the furnace. It will also be apparent that in each of the forms of my invention herein illustrated this cover is connected to and correlated with the cover closing the outer opening in such manner that movement of 25 the outer cover to expose the outer opening automatically closes the inner opening. It will therefore be obvious that the forms of 30 my invention herein disclosed accomplish the principal object of my invention.

35 On the other hand, it will at the same time be obvious to those skilled in the art that the particular embodiments of my invention herein shown and described may be variously changed and modified without departing 40 from the spirit of my invention or sacrificing the advantages thereof. It will therefore be understood that this disclosure is illustrative only and that my invention is not limited thereto.

45 I claim:

1. Means for humidifying the air of a hot air furnace, comprising a receptacle provided with an outer opening arranged to permit the insertion of water into said receptacle from the exterior of said furnace, and an inner opening arranged to permit the vaporization of such water into the air within said furnace, and a unitary cover arranged to close said openings alternately

to thus prevent water being inserted into 55 said receptacle through said outer opening splashing through said inner opening into the interior of said furnace.

2. Means for humidifying the air of a hot air furnace, comprising an open top receptacle having its open top divided by the furnace wall into an outer opening lying outside said furnace wall and arranged to permit the insertion of water into said receptacle from the exterior of said furnace, 60 and an inner opening lying inside said furnace wall and arranged to permit the vaporization of such water into the air within said furnace, and a unitary cover arranged to close said openings alternately to thus prevent water being inserted into said receptacle through said outer opening splashing through said inner opening into the interior of said furnace.

3. Means for humidifying the air of a hot 75 air furnace, comprising a receptacle provided with an outer opening arranged to permit the insertion of water into said receptacle from the exterior of said furnace, and an inner opening arranged to permit the vaporization of such water into the air within 80 said furnace, and a unitary cover of a size to close either of said openings and slidably mounted to close said openings alternately to thus prevent water being inserted into said receptacle through said outer opening splashing through said inner opening into the interior of said furnace.

4. Means for humidifying the air of a hot 90 air furnace comprising an open top receptacle having its open top divided by the furnace wall into an outer opening lying outside said furnace wall and arranged to permit the insertion of water into said receptacle from the exterior of said furnace, 95 and an inner opening lying inside said furnace wall and arranged to permit the vaporization of such water into the air within said furnace, and a unitary cover of a size to close either of said openings and slidably mounted to close said openings alternately to thus prevent water being inserted into 100 said receptacle through said outer opening splashing through said inner opening into the interior of said furnace.

In testimony whereof, I hereunto affix my signature.

SAM HERSCHE
